UNITED STATES PATENT OFFICE.

FULTON D. RING, OF CONWAY, KANSAS.

TWINE-TENSION FOR BINDERS.

SPECIFICATION forming part of Letters Patent No. 690,186, dated December 31, 1901.

Application filed April 18, 1901. Serial No. 56,478. (No model.)

To all whom it may concern:

Be it known that I, FULTON D. RING, a citizen of the United States, residing at Conway, in the county of McPherson and State of Kansas, have invented certain new and useful Improvements in Twine-Tensions for Binders, of which the following is a specification.

My invention relates to twine-tensions for binders; and my object is to produce a device 10 of this character applicable to any of the approved binders on the market with which the twine may be more easily and quickly secured in or withdrawn from engagement than with the tension devices at present in use.

15 A further object is to provide a device of this character which is of simple, strong, durable, and cheap construction and which performs its function of holding the twine efficiently.

20 To these ends the invention consists in certain novel and peculiar features of construction and combinations of parts, as hereinafter described and claimed, and in order that it may be fully understood reference is to be had 25 to the accompanying drawings, in which—

Figure 1 represents a view principally in side elevation of a twine-tension embodying my invention, the same being shown as applied to the binding-platform of a harvesting-machine. Fig. 2 is an inverted plan view 30 of the same. Fig. 3 is a front view of the same.

In the said drawings, 1 designates the platform of a harvesting-machine, which is adapted to extend horizontally or at an angle, according to the type of machine of which it 35 forms a part.

The tension device is constructed as follows: 2 designates the base-plate, preferably of cast metal and provided near its rear end 40 with the depending loop 3 and near its front end with the depending ears 4, arranged at right angles to the loop and equal distances from the longitudinal center of the plate. Rearward of and nearer the center of the 45 plate are a pair of guide-arms 5, depending from the plate, and forward of said arms and in line with the longitudinal center of the plate are the depending bearing-arms 6 and 7, the latter being of the type and configuration hereinafter described.

7^a designates a longitudinally-extending bolt mounted in said bearing-arms and for-

ward of bearing-arm 7 reduced diametrically to form a screw-threaded portion 8, and journaled upon said bolt is a corrugated roller 9, 55 the forward end of said roller being tapered to conical or frustum shape, as at 10, this tapered portion being smooth or non-corrugated.

11 designates a conical nut which engages the threaded portion 8 of the bolt and secures the latter and said roller reliably in position, and in this connection it will be noticed that the taper of said nut corresponds to the taper of the frustum 10 and the interposed enlargement or head 7^b of bearing-arm 65 7, as shown clearly in Fig. 1.

12 designates a second corrugated roller arranged vertically below roller 9 and of precisely the same construction, except that its frustum - shaped portion 13 is preferably 70 longer. (See Fig. 1.) This roller 12 is journaled upon the cylindrical end 14 of a tension-plate 15, the latter being of spring metal, preferably, and formed at the front end of cylindrical portion 14 with a reduced threaded 75 portion 16, engaged by a nut 17, similar to nut 11, and by reason of the greater length of frustum 13 than of frustum 10 said nut occupies a position vertically below nut 8.

Tension-plate 15 is formed at its rear end 80 with a depending forwardly-disposed hook 18, pivotally engaging loop 3 and detachably connected therewith, and is also provided between said loop and guide-arms 5 with the central hole 19, through which extends bolt 20, depending from platform 1 and plate 2.

The roller 12 is held with a yielding pressure toward its companion roller by means of the nut 21 upon the lower end of bolt 20 and the spiral spring 22 upon said bolt and interposed between said nut and the base-plate, the nut being adapted to be adjusted for the purpose of increasing or decreasing the tension, as will be readily understood, and in order that said bolt may also serve as a means 95 for securing plate 2 reliably to platform 1 it is provided with a threaded portion 23, engaged by a clamping-nut 24 just below said plate.

Extending vertically at the outer sides of 100 ears 4 and about centrally of the corrugated portions of the rollers are the twine-guides 25, the same being preferably in the form of rods bent spirally or convoluted at their lower ends.

to provide the guide-eyes 26 centrally between the rollers in order that the twine *a*, extending therethrough and between said rollers, shall extend in a straight line. Said rods extend up through plate 2 and platform 1 and are engaged at their upper ends by retaining-nuts 27, and in order to secure them more reliably in position they are convoluted to provide loops 28 to receive short bolts 29, the latter extending also through ears 4, nuts 30 engaging the outer ends of said bolts to clamp said loops tightly up against the ears, as shown clearly.

In practice to secure the twine in operative position it is first threaded spirally in the guide-eyes 26 and then pulled in opposite directions through said eyes. This action moves the intermediate portion laterally in the direction indicated by arrow *a'* into the flaring or V-shaped mouth formed by and between the tapered front ends of the rollers, nuts 11 and 17, and bearing-arm 7 and automatically between the corrugated portions of said rollers, the lower roller yielding sufficiently to permit this object to be accomplished easily and quickly, and in this connection will be seen the reason why the head or enlargement 7^b corresponds to the form and configuration of said roller and said nut. In such position the twine is fed in the usual manner, the lower roller yielding to pass all knots or irregularities without breaking or injuring the twine and without permitting the tension to relax, as will be readily understood.

The manipulation above described is reversed in removing the twine from between the rollers.

From the above description it will be apparent that I have produced what I term a "self-threading" tension device for harvesting machines which embodies the features of advantage enumerated as desirable in the statement of invention, and while I have illustrated and described the preferred embodiment of the invention it is to be understood that it is susceptible of minor changes in the form, proportion, detail construction, and arrangement of the parts without departing from the spirit and scope or sacrificing any of the advantages.

Having thus described the invention, what I claim as new, and desire to secure by Letters Patent, is—

1. In a tension device for binders, the combination of a pair of parallel tension-rollers, held together with a yielding pressure, and formed with non-corrugated tapering front ends to provide a V-shaped or flaring mouth, and a pair of twine-guides, arranged at opposite sides of said rollers, substantially as described.

2. In a tension device for binders, the combination of a pair of parallel tension-rollers, held together with a yielding pressure, and having their front ends of non-corrugated tapering form to provide a flaring mouth, and a pair of twine-guides at opposite sides of the rollers, and bent or convoluted at their lower ends to form eyes which receive and hold the twine between and in engagement with the rollers, substantially as described.

3. In a tension device for binders, the combination of a pair of corrugated tension-rollers, held together with a yielding pressure, and tapering form to provide a flaring mouth, and a pair of twine-guides at opposite sides of said rollers and bent or convoluted at their lower ends to form eyes which receive and hold the twine between and in engagement with the corrugated portions of the rollers, substantially as described.

4. In a tension device for binders, the combination of a plate secured to the binder-platform, a roller supported therefrom and having its front end of tapering formation, a tension-plate pivotally supported from the first-named plate, a roller journaled upon its front end, and tapered to correspond with the first-named roller, means for holding said rollers together with a yielding pressure, and twine-guides at opposite sides of said rollers, substantially as described.

5. A tension device for binders, comprising a plate provided with a pair of bearing-arms, the foremost one having a tapered head or enlargement, a bolt journaled in said bearing-arms, and provided with a threaded portion projecting forward of the arm having the head or enlargement, a roller journaled on said bolt, and having its front end tapered and bearing against the tapered head of said bearing-arm, a tapering or conical nut engaging the threaded end of said bolt and bearing against the opposite side of said bearing-arm, a tension-plate pivoted to the first-named plate, and guided to operate toward or from said roller, a companion roller journaled on said plate and provided with a tapered front end, a nut engaging the front end of said tension-plate and holding said roller thereon, a spring holding said plate pressed toward the first-named roller, and twine-guides depending from the first-named plate at opposite sides of said rollers, substantially as described.

In testimony whereof I affix my signature in the presence of two witnesses.
